UNITED STATES PATENT OFFICE.

WILLIAM L. MURPHY, OF SAN FRANCISCO, CALIFORNIA.

DESIGN FOR A BED.

49,273.

Specification for Design.

Patented June 27, 1916.

Application filed April 1, 1915. Serial No. 18,615. Term of patent 14 years.

To all whom it may concern:

Be it known that I, WILLIAM L. MURPHY, a citizen of the United States, residing in the city and county of San Francisco, State of California, have invented a new, original, and ornamental Design for Beds, of which the following is a specification, reference being had to the accompanying drawing, forming part thereof.

The figure is a perspective view of the bed, showing my design.

I claim:

The ornamental design for a bed, substantially as shown.

WILLIAM L. MURPHY.

Witness:

H. G. PROST.
